UNITED STATES PATENT OFFICE

ANDREW LITTLE, OF NEW YORK, N. Y.

DESIGN FOR PRINTING-TYPE.

Specification forming part of Design No. 6,359, dated January 21, 1873.

To all whom it may concern:

Be it known that I, ANDREW LITTLE, of the city, county, and State of New York, have invented and produced a new and original Design for Printing-Type, of which the following is a specification:

The nature of my design is fully represented in the accompanying typographic impression, to which reference is made.

What I claim as new is—

The design for printing-type, as herein shown.

ANDREW LITTLE.

In presence of—

AUGUSTUS S. DOANE,
Wm. HASTINGS.
